Attorney, Agent, or Firm—Mark C. Jacobs

[57] CLAIM

The ornamental design for a sprinkler head protector or similar article, substantially as shown and described.

DESCRIPTION

FIG. 1 is a perspective view of a sprinkler head protector showing my new design.

FIG. 2 is a fragmentary perspective view thereof.

FIG. 3 is a cross sectional view taken on line 3—3 of FIG. 1.

The broken line representation of a sprinkler head and the ground in FIG. 3 are for purposes of illustration only.

FIG 1

FIG. 2

FIG. 3
